Specification for Design.

Patented July 10, 1917.

Application filed May 5, 1917. Serial No. 166,758. Term of patent 14 years.

To all whom it may concern:

Be it known that I, FRANK T. FAIRCLOTH, a citizen of the United States, residing at San Francisco, in the county of San Francisco and State of California, have invented a new, original, and ornamental Design for a Tread for Automobile-Tires, of which the following is a specification, reference being had to the accompanying drawing, forming part thereof.

Figure 1, is a plan view of an automobile tire showing my new design on the tread

thereof. Fig. 2, is a sectional plan view of an automobile tire showing my new design on the tread thereof. Fig. 3, is a cross cut section of same.

I claim—

The ornamental design for a tread for automobile tires, as shown.

FRANK T. FAIRCLOTH.
